(57) **CLAIM**

The ornamental design for a postoperative compression binder, as shown and described.

DESCRIPTION

FIG. 1 is a front perspective view of the outside of a postoperative compression binder showing my new design in use; FIG. 2 is a plan view of the outside of the open postoperative compression binder of FIG. 1 laid out flat; FIG. 3 is a plan view of the inside of the open postoperative compression binder of FIG. 1 laid out flat; FIG. 4 is a top view of the upper side of the open postoperative compression binder of FIG. 1; FIG. 5 is a bottom view of the lower side of the open compression binder of FIG. 1; FIG. 6 is an end view of the first end of the open postoperative compression binder of FIG. 3; and, FIG. 7 is an end view of the second end of the open postoperative compression binder of FIG. 2. The broken line showing of a human body in FIG. 1 is for the purpose of illustrating environment and forms no part of the claimed design. The broken line showing on the postoperative compression binder represents stitching which forms a part of the claimed design.

1 Claim, 6 Drawing Sheets
